UNITED STATES PATENT OFFICE.

HENRY F. PHILLIPS, OF AUBURN, NEW YORK.

IMPROVEMENT IN HARVESTER-RAKES.

Specification forming part of Letters Patent No. **86,178**, dated January 26, 1869.

To all whom it may concern:

Be it known that I, HENRY F. PHILLIPS, of Auburn, in the county of Cayuga and State of New York, have invented certain new and useful Improvements in Reel-Rakes for Harvesting-Machines; and that the following is a full, clear, and exact description of the same, reference being had to the accompanying drawings, making a part of this specification, in which—

Figure 1 represents a perspective view of the reel-rake and so much of a harvesting-machine as will illustrate the operation of said rake. Fig. 2 represents a vertical section through the gear-stand, the rakes being omitted. Fig. 3 represents a top view of the gear-plate, and Fig. 4 represents a top view of the cam-plate and its latch or switch and of the pulley below it. Figs. 5 and 6 represent details of the rake-moving devices not so clearly shown in the other figures.

Similar letters of reference, where they occur in the separate figures, denote like parts in all of the drawings.

My invention relates to what is termed a "reel-rake"—that is, a series of revolving and rising-and-falling rakes, that also perform the duty of a reel by drawing the standing grain to the cutters, where it is severed from the stubble, and then the rakes, at the will of the operator, sweep off the grain onto the ground in a gavel, and out of the way of the return swath; and my invention consists in the construction and combination of parts by which the above results are attained, and which will be hereinafter more minutely described, and particularly set forth in the claims.

To enable others skilled in the art to make and use my invention, I will proceed to describe the same with reference to the drawings.

A represents the grain table or platform of a harvesting-machine, and B the outside divider thereon.

Upon the inner front corner of the platform is arranged a pillar or support, C, in which is set a vertical fixed spindle, D, for supporting the pulley E and driving-plate F, to which the pulley is keyed or attached, so that they shall turn together.

The cam-plate G is stationary, being held

by the arms H, the hub I of said arms being permanently attached to the pillar C, or held by a set-screw, as at J.

The upper portion of the driving-plate F is simply a rim with a large interior opening, and this portion of the plate carries the studs K, for supporting the rakes laterally against the resistance of the grain, and also carries the trigger L, for setting the switch in the camway of the cam-plate for causing one of the series of rakes to clear the platform of the cut grain, and further forms a support for the springs M under the rake-stales, the particular duties of all of which will be described hereinafter.

On what may be termed a central portion of the driving-plate F—viz., that portion between the rim above mentioned and the pulley E—is arranged a series of lugs, N, to which are pivoted, respectively, by the pins a, the rake-arms O, to which the rake stale or handle is bolted, one to each, said arms being of metal, and furnished with a segmental gear, b, Fig. 5. The wood portions P of the rakes are bolted to these segment rake-arms O.

In recesses or guideways c c formed in the driving-plate are laid racks Q, Fig. 6, each rack having projecting below it a stud and friction-roller, R, said roller passing through an opening, d, in the working plate, and extending down so as to work in the camways S S' in the cam-plate G, and the stud e is made sided, so as to fit nicely and move freely through the opening d as the roller runs in the camways.

In the camway S there is a switch, T, pivoted at f, and operated from the exterior by a lever, U, automatically by the trigger L every time it comes around and against said lever U; or the trigger may be removed and a cord attached to the lever by its hole g or otherwise, and extending to the driver, who can operate it at his will, and make any one of the series of rakes that he chooses take the inner camway, S, and cause that one of the series to rake the grain from the platform, while all the others, unless similarly directed by the driver, act as reels to draw in the grain to the cutters and then pass around above the platform.

The moving of the lever U in the direction of the arrow there shown opens the switch T,

and causes the roller of the first rake that comes around to take the camway S, and thus moving its rack more toward the center of motion, and drawing the forward part of the rake down closer to the platform. When the roller has passed the switch and camway S a spring, h, moves the lever U, which, in turn, closes the switch, and the rollers of the other following rakes taking the camway S' do not draw down the rakes, and thus they only act as beaters or reels.

The more the racks slide toward the center of motion of the reel-rakes the more they (the rakes) are drawn down, and, *per contra*, the farther the racks are from the center of motion the higher the rakes are raised or remain.

Each rake has underneath it a spring, M, which performs three duties: First, it eases its rake from jar when dropping from its more vertical position; second, it tends, through the segment and rack, to cause its roller to follow the cam-path S' by crowding it against the outer flange of the camway, and thus easily passing the switch; and, thirdly, it starts its rake into its upward position, which is completed by the sliding rack.

The switch V is merely to form one side of the camway S when a roller is passing through that way, and to keep said roller in its proper path. This switch needs no closing device, as the next roller that comes around takes the camway S', and, rolling against the switch, pushes it shut.

The cam-plate G and the driving-plate F are so located with regard to the cutting-line of the machine as that the rakes, when about to draw in the grain to the cutters, shall drop low enough to insure their bringing it into the cutters, and as soon as the rakes, or rather such of them as act as reels, pass the cutter, they rise up and pass over the platform without touching the cut grain upon it, and all of them before they reach the main frame still farther rise up and into a more vertical position, so as, in their circuit, not to interfere with the main frame or the driver riding thereon; or the rakes may be allowed to drop a little below the plane of the cutters and in advance of them, and approach the cutters by a sweeping and upwardly-rising motion, so as to lift up the grain in advance of the cutters.

The pitch of the cam-ledge at i, Fig. 4, which is nearer to the center of motion than at any

other part of said ledge, allows the rakes to drop lower at that than at any other point in the beat of the cam, and from that point the rakes gradually rise, as above mentioned.

In addition to the three duties above mentioned that the springs M under each of the rakes perform, there is a fourth and important one, as follows: They prevent the rake-teeth from dropping into the cutters by taking up all the slack or lost motion.

The tracks or camways S S' are formed by or inclosed between the walls or flanges j j and the switches T V and their abutment W, all of which are in vertical planes parallel to each other.

Having thus fully described my invention, what I claim therein as new, and desire to secure by Letters Patent, is—

1. In combination with a driving or working plate that carries a series of pivoted or hinged rakes with a cogged segment on their hubs, the sliding rakes, working in or with said segment, for raising and lowering said rakes, substantially as and for the purpose described.

2. In combination with the working plate and its cogged rake-hubs and racks, the stationary cam-plate, with its camways and switch, when a friction-roll or its equivalent on each of the racks extends into and is operated by said camways, substantially as and for the purpose described.

3. In combination with the rakes, the springs underneath them, when said springs serve not only to prevent the jar of the rakes when dropping, but also hold the friction-rolls of their respective racks out against the wall of the camway, to cause the rakes to properly pass over the table or platform, and prevent the rake-teeth from dropping into the cutters by taking up all the slack or lost motion, substantially as described.

4. In combination with the track or camways and the switches placed therein, which give the rakes their rising-and-falling motion, the arranging of the walls or flanges of said camways and switches in vertical planes parallel to each other, substantially as described and represented.

HENRY F. PHILLIPS.
